United States Patent Office.

DEXTER SYMONDS, OF MARLOW, NEW HAMPSHIRE.

Letters Patent No. 76,957, dated April 21, 1868.

IMPROVED PROCESS FOR TANNING.

The Schedule referred to in these Letters Patent and making part of the same.

TO ALL WHOM IT MAY CONCERN:

Be it known that I, DEXTER SYMONDS, of Marlow, in the county of Cheshire, in the State of New Hampshire, have invented a new and improved Tanning Process, of which the following is a full, clear, and exact description, reference being had to the accompanying drawings, making part of this specification, in which—

Figure 1 is a longitudinal vertical section of the apparatus which I use for producing tanning-liquid from bark or other substances.

Figure 2 is a top view of the same, after a portion of the cylinder A has been removed, to show the grate on which the bark or other substance is burned.

Figure 3 is a front end view, and

Figure 4 a transverse section of figs. 1 or 2.

Figure 5 is a transverse section on the line Y Z of fig. 1.

This invention consists, first, in the process of producing or obtaining liquid from bark or other substances; second, in the application of such liquid to hides or skins to be tanned; and, third, in the liquid as a new production for tanning purposes.

In carrying out my invention I first provide an apparatus, in which the bark or other substances are consumed by regulated combustion, and in which the vaporized products of such combustion are condensed, collected, and drawn out for use.

This apparatus consists of a box or cylinder, A, which has a grate, B, above which is a combustion-chamber, C, and beneath the grate is an ash-pit, D.

From the rear end of the cylinder, and leading from the combustion-chamber, a pipe or tube, E, extends into and nearly the whole length of a box or trough, G, filled with cold water. The rear end of said tube is turned upward and extends above the water. All the smoke and vapor from the burning substance pass into the tube E, where the vapor is condensed, but the smoke passes out at the end, F, of the tube or pipe.

Connected with the under side of the tube E, and near the rear end, is a smaller tube, a, which extends downward through the water and the bottom, b, of the trough, and the condensed vapor which collects in tube E passes through the tube a into a tub, H, or other receptacle, from which it may be removed for use or transportation.

The bark, or other substance from which my tanning-liquid is produced, is thrown into the combustion-chamber through the feed-door I, and on to the grate B, where it is set on fire and burned, and by admitting sufficient atmospheric air through the draught-door, k, or any other opening below or above the grate, and by regulating the combustion by such draught-opening or otherwise, a brisk fire and rapid combustion is the result.

This rapid combustion produces a large supply of vapor, which, with the smoke, passes into the pipe E, where the vapor is condensed and collected and drawn out, as described, while the smoke passes off through the rear end of the pipe.

The particular construction or arrangement of the apparatus for burning the bark or other substance, is of no great importance, since any ordinary stove or furnace may be adapted for the burning-operation, provided the draught or current of air can be controlled or regulated so as to produce rapid or ordinary combustion, and where the pipe or pipes, tube or tubes, arranged for conveying the smoke and vapor from the burning substance, pass into or through a condenser like a trough, filled with cold water, as described, which will condense the vapor, and produce my new and improved tanning-liquid, which I call "pyro-tannin."

This new and improved tanning-liquid is produced in large quantities from spent bark, or bark which has been deprived of all its tanning properties that can be extracted by leaching, steeping, or other ordinary process, and the liquid produced or obtained from spent bark, by my process, is in every respect as good for tanning purposes as the liquid produced from fresh bark, and in my opinion, such improved tanning-liquid obtained from spent bark, is superior to the tanning-liquid obtained from fresh bark by leaching or by steeping or by other ordinary process.

I do not confine myself to the use of spent bark for obtaining liquid to tan hides or skins, but I use fresh bark, or any other substance from which tanning-liquid can be obtained by my process.

In my new tanning-process, and in the use of my new and improved tanning-liquid or "pyro-tannin," for tanning hides and skins, after the hair has been removed from the hides by the liming-process, or by any other well-known process of removing said hair, the hides are then subjected to the action of the "pyro-tannin," prepared as above described, and without any intervening process between the liming and the tanning-process.

This pyro-tannin not only neutralizes the lime, but quickly penetrates and tans the hides in a superior manner, without injury to the fibres of the hide, and with a great saving of time in preparing and tanning, so as to produce good leather.

Hides and skins are tanned by my improved tanning-process without removing the hair or the fur, and without any other operation, except the usual soaking and fleshing of the hide. No other process of preparation is necessary to fit the hide or the skin for my tanning-process, which produces much softer and tougher leather than the ordinary process of tanning.

After the hides or the skins have been partly or wholly tanned by my improved process of tanning, and to change the character or the appearance of the leather, as to change the color or to make the leather harder or stiffer, I remove the partly or the wholly-tanned hides or skins or leather from the "pyro-tannin," and subject them to the action of ordinary tanning-liquid, procured or extracted from fresh bark, by leaching or steeping, or by other ordinary process.

Hides which have been unhaired, or which have had the hair removed by the liming-process and then tanned or partly tanned by my improved process, before being subjected to the action of ordinary bark-liquor, should be washed or scoured in the usual way, so as to remove any particles of neutralized lime which may be retained in or upon the surface of the hide or leather.

The pipe or tube E in the condensing-apparatus should be long enough to condense all the vaporized products from the burning substance, or, if preferred, several of such pipes may be employed in the same manner, or by having their ends connected with return-bends, so as to form one continuous passage for smoke and vapor, as in a coil or worm, which may be used when immersed in cold water, or cold air may be blown or drawn into an enclosure around and in contact with such coil or other pipe or pipes, so as to condense all the vapor, but allow the smoke to pass through the pipe or other conducting-device.

In tanning hides or skins by my improved tanning-process, the same apparatus may be used, and the same machinery for working the hides, that are used in the ordinary process of tanning hides, and as all the drenching and other processes for neutralizing the lime and preparing the hides for tanning are dispensed with in my process, much less care and labor are required to carry on and perfect the operation of tanning than by the ordinary process.

Thus it will be readily seen that the "pyro-tannin" or new tanning-liquid in my improved tanning-process not only tans the hides, but is a substitute for all the ordinary processes between the liming-process and the final process, which produces the perfectly-tanned leather.

What I claim as new, and desire to secure by Letters Patent, is—

1. I claim the process, substantially as described, of producing or obtaining from bark or other substances liquid for tanning hides and skins.
2. I claim the application of such liquid to hides or skins to be tanned.
3. I claim the liquid herein described as a new production for tanning purposes, when produced or obtained by the process described.

DEXTER SYMONDS.
